(57) **CLAIM**

The ornamental design for a display screen with a graphical user interface as shown and described.

DESCRIPTION

FIG. 1 is a front elevational view of a first image of a graphical user interface showing our new design; FIG. 2 is a front elevational view of a second image thereof; FIG. 3 is a front elevational view of a third image thereof; FIG. 4 is a front elevational view of a fourth image thereof; FIG. 5 is a front elevational view of a fifth image thereof; FIG. 6 is a front elevational view of a sixth image thereof; FIG. 7 is a front elevational view of a seventh image thereof; FIG. 8 is a front elevational view of an eighth image thereof; FIG. 9 is a front elevational view of a ninth image thereof; FIG. 10 is a front elevational view of a tenth image thereof; FIG. 11 is a front elevational view of an eleventh image thereof; and,

FIG. 12 is a front elevational view of a twelfth image thereof.

The appearance of the image sequentially transitions between the images shown in FIGS. 1-12 from FIG. 1 to FIG. 12. The process or period in which one image transitions to another image forms no part of the claimed design. The broken line showing the display screen and other elements forms no part of the claimed design.
